DESIGN FOR A BROOCH OR SIMILAR ARTICLE

Ruth M. Reed, Hinton, Okla.

Application April 5, 1943, Serial No. 109,907

Term of patent 7 years

To all whom it may concern:

Be it known that I, Ruth M. Reed, a citizen of the United States, residing at Hinton, in the county of Caddo and State of Oklahoma, have invented a new, original, and ornamental Design for a Brooch or Similar Article, of which the following is a specification, reference being had to the accompanying drawing forming part thereof, wherein Figure 1 is a view in front elevation of a brooch embodying my new design; and Figure 2 is a view in side elevation.

I claim:

The ornamental design for a brooch or similar article, as shown.

RUTH M. REED.
